UNITED STATES PATENT OFFICE.

JOHN PARSONS, OF WESTERLY, RHODE ISLAND.

GARMENT.

1,134,901.

Specification of Letters Patent.

Patented Apr. 6, 1915.

Application filed May 14, 1914. Serial No. 838,576.

To all whom it may concern:

Be it known that I, JOHN PARSONS, a citizen of the United States, residing at Westerly, in the county of Washington and State 5 of Rhode Island, have invented certain new and useful Improvements in Garments; and I do declare the following to be a full, clear, and exact description of the invention, such as will enable others skilled in the art to 10 to which it appertains to make and use the same.

My invention relates to improvements in garments and has for its object to provide a device of the character described, in which a 15 coat shirt and a pair of drawers are formed as a single article, which may be easily and inexpensively constructed and which will overcome the great amount of chafing usually caused by seams coming into contact 20 with the crotch of the wearer.

With this object in view, the invention resides in certain novel features of construction and combination herein described and claimed and shown in the drawings wherein:

25 Figure 1 is a front elevation of a garment constructed in accordance with my invention, the flap being closed; Fig. 2 is a similar view with the flap partially open; Fig. 3 is an inner side elevation of a portion of the 30 back of the garment, the inserts being folded to more clearly illustrate the contour of a pair of notches to be described; Fig. 4 is a similar view with a portion of the flap and the garment folded to illustrate the formation 35 of one of the inserts; and Fig. 5 is a plan view of one of the inserts detached.

In the accompanying drawings, I have shown my improved garment as including a coat shirt 1, the upper portion of which is 40 of common construction. The lower end of the back of the shirt, however, is formed with a substantially triangular flap 2 which is integrally united with said back by a contracted neck 3, the latter being formed by 45 providing a pair of substantially ovate notches 4 in the shirt back, said notches having their contracted ends opening through the extreme lower edge of said back. As clearly seen in the drawings, the neck 3 is 50 adapted to be positioned in the crotch of the wearer and is entirely free from seams at its central portion, thus preventing undue chafing.

By reference to the drawings, it will be seen that the front, sides and rear portions 55 of the lower end of the garment constitute outer leg engaging members, these parts being formed sufficiently long for this purpose. The inner leg engaging portions of the garment, however, are in the form of 60 substantially rectangular inserts 5, the latter being stitched along their upper and outer edges to the material surrounding the notches 4. As most clearly seen in Fig. 4, the free edges of said inserts form continuations of the flap 2 and of the lower edge of the garment, the free corners of said inserts being formed with buttonholes 6 as are likewise the three corners of the flap 2, as indicated at 7, these buttonholes 6 and 7 engaging 70 buttons 8 and 9 which are suitably positioned on the front of the garment.

By the above set forth construction, it will be seen that I have produced an extremely simple and inexpensive garment yet one 75 which will be highly efficient in operation.

I claim as my invention:

A garment comprising a coat shirt having a triangular flap formed integrally with the lower end of its back and connected thereto 80 by a reduced neck, said lower back end having a pair of substantially ovate notches in its lower edge adjacent the opposite sides of the neck portion of the flap, substantially 85 rectangular inserts having one corner rounded, said inserts being secured in said notches with the side edge and end edge connected by the rounded corner stitched to the material surrounding the notches, the remaining side and end edges of said inserts 90 constituting continuations of the lower end of the garment and of the triangular flap, said inserts forming seamless inner leg-engaging portions, fastening elements on the shirt front and co-acting fastening elements 95 on the free corners of the flap and on the free corners of the inserts.

In testimony whereof I have hereunto set my hand in presence of two subscribing witnesses.

JOHN PARSONS.
